UNITED STATES PATENT OFFICE

FREDERICK L. FULLER, OF WEST ORANGE, NEW JERSEY, ASSIGNOR TO INTERNATIONAL TIME RECORDING COMPANY OF NEW YORK, OF ENDICOTT, NEW YORK, A CORPORATION OF NEW YORK

TIME RECORDER

Application filed April 8, 1929. Serial No. 353,643.

The present invention relates to a time recording mechanism which is especially adapted for use in small places of business where only a comparatively few people are employed. The machine provides a continuous time sheet upon which are recorded in one line registrations of the same character; that is, all registrations in any one horizontal line are either all "In" or "Out" registrations. 10 The vertical columns represent registrations for different employees. When an employee arrives at the place of business the indicator on the machine is turned to "In" and the employee registers by placing the registering handle in the proper position and lifting the same in a manner to be explained later. When this employee registers "Out" the indicator is moved to "Out" and registers in the same manner. This operation feeds the time sheet so that his "Out" registration appears in vertical alinement under his "In" registration so that after several employees have registered "In" and "Out" the record sheet shows a plurality of columns, each column representing some individual's registration showing successive times of arrival and departure.

An object of this invention is to provide a time recorder having a carrier for a time sheet which may be shifted to subsequent printing position to identify the arrival or departure of the operator and at the same time be adjusted to a different printing position to identify the operator registering.

A further object of the invention is to provide a continuous time sheet shiftable in linear direction to subsequent printing position and in subsequent and transverse direction relatively to the printing device into different printing positions.

Another object of the invention is to provide shifting means for a feed roller for a continuous time sheet which may be disengaged from said feeding roller so that the time sheet may be moved independent of said shifting means.

Still another object of the invention is to provide a new and improved ribbon feed and reversing mechanism for a time recorder.

Still another object of the invention is to

provide a new platen mechanism for time recorders wherein the platen is slidably mounted and pressed against the type wheels.

Various other objects and advantages of my invention will be obvious from the following particular description of one form of mechanism embodying the invention or from an inspection of the accompanying drawings; and the invention also constitutes certain new and novel features of construction and combination of parts hereinafter set forth and claimed.

In the drawings:

Fig. 1 is a front view of the clock and recording mechanism.

Fig. 2 is a plan view of the recording mechanism.

Fig. 3 is a section taken on line 3—3 of Fig. 2.

Fig. 4 is a section taken on line 4—4 of Fig. 2.

Fig. 5 is a section on line 5—5 of Fig. 4.

Fig. 6 is a detail view of the ribbon feeding and reversing mechanism.

Fig. 7 is a detail view of the manual means for feeding the record sheet.

Fig. 8 shows a portion of a record sheet with registration thereon.

Fig. 9 is a detail view of the receiving roller on which the record sheet is wound.

Fig. 10 is a detail of the impression mechanism.

The time mechanism as shown in Fig. 1 comprises the well known pendulum clock which is mounted on a frame generally designated with reference numeral 2 and which drives by means of a train of gears the hands 3 and 4 of the clock, the clock mechanism also driving a shaft 1 turning type wheels of the printing mechanism in accordance with the clock mechanism. The printing mechanism is fixed to the support plate of a clock where-as a time sheet carrier is adjustable by means of a handle 5 into different printing positions relative to the printing device.

As may be seen from Fig. 1 there are provided in the housing 6 ten adjusting positions each for an individual. A knob 7 is further provided to shift the continuous time sheet for one line to the following printing posi-

tion. This shifting operation is to permit a differentiation between registrations for arrival and registrations for departure. That is, when an individual registers on arrival he must shift the sheet from the same position before registering for departure. "In" and "Out" indications on the casing 6 together with a point at 32 on the knob 7 permits the operator to determine if the sheet requires shifting. The time sheet carrier carries the record which is shiftable between the type wheels and a platen which is pressed against the type wheel by means of a handle 5 when this handle is lifted in its respective adjusted position thus effecting time registration on the record sheet.

Time sheet carrier

The housing 6 includes two upwardly bent side plates 8 and 9 which carry a shaft 10 fixed thereto (Fig. 5). Slidably mounted upon this shaft is the time sheet carrier which comprises the side plates 11 and 12 carrying the receiving roll 13 and the paper supply roll 14 (see Fig. 4). Fixed upon both sides of plates 11 and 12 are slotted guiding members 15 and 16 guiding the ends of a shaft of an auxiliary roll 17 which is provided to secure a proper tension of the time sheet at all times. Integral with the side plates 11 and 12 are bifurcated projections 18 and 19 (Figs. 2 and 3), said bifurcations slidably engaging the edge of a plate 20 fixed to the housing, the purpose of which is to prevent rotation of the time sheet carrier about the shaft 10. A yoke member 21 (Figs. 3, 4 and 5) is pivotally mounted on sleeves 21' fixed in the side plates 11 and 12 which slide upon the shaft 10. This yoke member has fixed thereto a handle 5, which serves to effect printing operation in a manner to be explained later. Any transverse movement of the handle in either direction therefore will cause the time sheet carrying mechanism to be moved slidably along the shaft 10 the same distance and direction in which the handle is moved and thus the time sheet may be moved into any one of the ten registering positions indicated in Fig. 1.

In the upper part of the side plates 11 and 12 is journaled the axis 26 of the paper receiving roll 13 which has fixed thereto at one end a ratchet wheel 22 coacting with an actuating pawl 23 and with a retaining pawl 24. The retaining pawl 24 is pivotally mounted on side plate 11 and spring pressed against the ratchet wheel 22. The shifting pawl 23 is pivotally mounted on a lever 25 which is pivotally mounted at one end to the shaft 26 carrying the feeding roller 13. Fixed to the opposite end of said lever 25 is a cross rod 27 extending therefrom to a similar lever 25' which is also pivotally mounted on the opposite end of shaft 26. A hook 28 slidably engages the cross rod 27 to permit constant en-

gagement of said hook and cross rod while permitting the time sheet carrying mechanism to be moved transversely. When feeding operation is effected the hook 28 will be moved to the left (Fig. 3) and will consequently rock the cross rod 27 and plate 25 in a counterclockwise direction carrying the pawl 23 to a position to engage the next left hand tooth on the ratchet wheel 22 adjacent to that tooth previously engaged. Upon the return stroke the pawl 23 will engage the ratchet wheel and the receiving roll 13 will be spaced for one line.

Rotatably mounted on the same end of the shaft 26 as the pawls is a cam member 29 provided with a finger piece 30 integral with said cam and is normally held in the position shown in Fig. 3. The width of the pawls 23 and 24 is sufficient to overlap the plane of the cam 29 as well as the ratchet wheel 22 as shown in Fig. 5. With the cam 29 in the position shown in Fig. 3 the pawls 23 and 24 are engaging the ratchet wheel 22 so that no counterclockwise rotation of the receiving roll 13 will be permitted. When, however, it is desired to unwind the paper from said receiving roll the finger piece 30 is pushed to the left as viewed in Fig. 3 which rotates the cam 29 clockwise and cams the pawls 23 and 24 out of engagement with the ratchet wheel 22. The receiving roll 13 may then be turned counterclockwise and the record sheet unwound and removed from said roll. One end of the time sheet is fixed to the feeding roll 13 by means of a spring rod 31 (Fig. 9) which has its bearing in the roll 13 and clamps the time sheet by cooperation with a groove formed in the feeding roll 13.

As the rod 31 fits tightly in its cooperating groove and has to be sprung into clamping position it will remain in this position until manually released. As has been explained the feeding roll 13 will be shifted the space of one tooth each time the hook 28 rocks cross rod 27 in a clockwise direction. This is effected if time registration is changed from an "In" registration to an "Out" registration or vice versa. The means for making this change from an "In" to an "Out" registration or vice versa includes a knob 7 fixed to a shaft 33 and journaled in the housing 6. At the opposite end of said shaft is fixed a cam member 34a having a series of high points 34b and a series of alining notches 34c (Figs. 1, 2, 3 and 7). Cooperating with said cam member is a rolling cam wiper 281 pivotally mounted on one end of a lever 35 which in turn is pivotally mounted at 37 to the housing 6. In the normal position shown in Fig. 7 the cam wiper 281 repose in one of the alining notches 34c, lever 35 being biased in a counterclockwise direction by a spring 39' fixed to said lever at one end and to the housing 6 at the other. The cam member 34a is therefore held impositively locked in

this normal position and will not be moved unless a manual turning action is exerted on the knob 7. The contour of the high points of the cam member is such that it can only be turned in a clockwise direction. When said cam member 34a is moved in a clockwise direction so that the cam wiper 281 is brought into the next succeeding alining notch the lever 35 is oscillated once about its pivot 37 as the cam wiper passes over the high point between the alining notches. The end of the lever 35 opposite to the cam wiper 281 engages a notch in the end of a lever 39 pivotally mounted on the shaft 10 (Figs. 4 and 7). The opposite end of lever 39 is pivotally connected at 40 to the hook member 28. When therefore the lever 35 is oscillated it causes a lever 39 to be oscillated about its pivot point thus oscillating the hook member 28 to the left and back again as shown in Fig. 4. This causes the paper to be spaced one line as previously explained.

"In" and "Out" indications 36 are alternately provided on the housing 6 (Fig. 1) in a position to be visible, around the periphery of the knob 7. An indicating pointer 32 is provided on the knob 7 and is located relative to the "In" and "Out" markings to permit the operator to observe whether or not the registration sheet is in the proper position for him to register. That is, if an operator is about to register on the machine upon his leaving and observes that the indicator 32 points to "In" he turns the indicator to the next "Out" indication. This prevents the operator from printing the "Out" registration on top of the previous "In" registration. As the knob 7 is turned to the successive "In" and "Out" registrations the continuous time sheet is spaced one line and is wound up on the receiving roll 13 and unwound from the supply roll 14.

Type mechanism

The type mechanism is controlled as has been stated above by the clock mechanism through shaft 1 which cooperates with a toothed wheel 42 (Fig. 2) meshing with a toothed wheel 43. Directly fixed on the shaft 50 of toothed wheel 43 is minute type wheel 44, the hour type wheel 45 being controlled by the minute type wheel 44 by means of a well known transfer device. This transfer device comprises a cam member 46 cooperating with a follower 47 fixed to a shaft 48 journaled in fixed plates 62 and 63 which constitute the supporting structure by the type wheel mechanism. Fixed to the same shaft is also a member 49 carrying a spring pressed pawl 51 pivoted thereon and spring pressed into cooperation with a ratchet wheel 50. Actuation of the ratchet wheel 50 causes identical actuation of the hour wheel 45 said hour wheel and ratchet wheel being fixed to a common sleeve 52 (Fig. 2) rotatably mounted

on the shaft 46' (Fig. 4) journaled in the side plates 62 and 63. When the minute wheel and therefore the cam 46 turns the follower 47 will be lifted by said cam and consequently will also lift member 49 together with the pawl 51. When the follower 47 drops from the high point of the cam the member 49 also dropping will cause the ratchet wheel 50 to be shifted by virtue of its coacting pawl 51 engaging with said ratchet wheel. The member 49 is spring pressed downward by a spring 49' (Fig. 4).

The shifting of said ratchet wheel therefore shifts the hour type wheel 45 for one unit this shift occurring for each revolution of the minute wheel 44. A pivotally mounted member 53 having a lug coacting with the ratchet wheel 50 is provided to normally lock said ratchet wheel and is cammed out of locking position by the pawl 51 upon the downward shifting stroke of said pawl. Inasmuch as this transfer mechanism is of old and well known construction in the time recorder art no further explanation is deemed necessary.

A star wheel 54 is provided in fixed relation on the same shaft with the minute type wheel 44, said star wheel cooperating with an alining projection 55 of a member 56 mounted in fixed relation on a shaft 101 which serves to align the type wheels properly for registration when printing is effected. The shaft 101 is rotatable by the member 56 and is journaled in the frame members 62 and 63. The yoke member 21 to which the handle 5 is fixed cooperates with one end of a lever 57 which is bifurcated, said member being pivoted at 10 and having on its other end a cam projection 58 which cooperates with a roller 59 pivotally mounted on the member 56. When a printing operation is effected the handle 5 is lifted thereby lifting the bifurcated end of the lever 57 and consequently rotating that lever counterclockwise about its pivot 10. The downward movement of the camming projection 58 acts upon the roller 59 to turn the lever 56 in a clockwise direction thus engaging the alining projection 55 with the star wheel 54. The member 56 is biased in a counterclockwise direction by a spring 56' which keeps the roller 59 in constant cooperation with its coacting cam member. The bifurcation in the lever 57 permits the handle to be shifted transversely at will and still maintain cooperative relation with the lever 57 through the cross bar of the yoke member 21.

Printing actuating mechanism

The printing mechanism is actuated by the counterclockwise rotation of the member 57 when the handle 5 is lifted as previously explained. A plate 65 rigidly supported to the base frame has provided at its upper end a groove in which is slidably mounted a printing hammer 68 carrying an impression block 130

68 of rubber or other suitable material, said groove being held at an angle to permit the hammer to be slid in a direction radial to the type wheels 44 and 45 (Figs. 3, 4, 5 and 10). At the upper end of the plate 65 adjacent to the type wheels and extending at right angles to the plane of said plate are two projections 67, one passing above the printing hammer and one passing below the same. Between the ends of said projection is fixed a pin 70 so that the plate 65, the two projections 67 and the pin 70 form four walls of an aperture through which the hammer 68 is free to slide and which holds the end of the hammer adjacent to the type wheel in cooperation with the groove. The opposite end of the hammer is bifurcated and said bifurcations straddle a stud 71 fixed to the frame 63 and which is provided with an enlarged head overlapping the bifurcations. This holds the rear end of the hammer in the groove while permitting said hammer to be freely moved toward the type wheels and acts as a limit stop for the movement of said hammer away from the type wheels. Extending into a slot in the printing hammer 68 is one end of a link 73 which is pivotally mounted therin by a pin (not shown) mounted transversely to said slot in said hammer. The opposite end of the link 73 is pivotally mounted by a stud 74 to a link 72 which is pivotally mounted at its opposite end to the stud 71. Also pivoted to said link 72 by means of a stud 75 fixed thereon is one end of a link 76 the other end being pivotally mounted on stud 76' (Fig. 10). The stud 76' is adjustably mounted in a cooperating slot 77 (Fig. 4) in the upper furcation of the lever 57 and is normally held in fixed relation thereto by the nut 77' (Fig. 10) which is screwed onto the stud 76'. The adjustment of this stud along its cooperating slot 77 adjusts the length of travel of the printing hammer 68 for a given movement of the lever 57.

45 When the handle 5 is raised the lever 57 is turned counterclockwise which in turn raises the lever 76 and causes the lever 72 to be moved in a clockwise direction which results in a toggle action between the links 72 and 73 tending to bring them into a straight line which moves the type hammer impression block 69 into cooperation with the type wheels 44 and 45 to effect printing.

Ribbon feeding and reversing mechanism

46 The printing ribbon 78 (Figs. 2 and 4) is fed between the type wheels 44, 45 and the time sheet. This ribbon is wound up in the usual way upon one of the two ribbon spools 79 and 80 depending upon the direction the ribbon is feeding. Each of the said spools is spring biased into cooperation with ratchet wheels 81 and 82 respectively so that both the spool and its cooperating ratchet wheel turn together about their respective

supporting axes. Associated respectively with ratchet wheels 81 and 82 are actuating pawls 83 and 83' and retaining pawls 84 and 84'. The actuating pawls 83 and 83' are pivotally mounted on two similar lever arms 85 and 85' respectively (Figs. 3, 4 and 6). Said levers are fixed to a shaft 101 journalled in the frame members 62 and 63 and are so located on said shaft to hold the pawls 83 and 83' in the same plane with their respective associated ratchet wheels 81 and 82. Retaining pawls 84 and 84' are likewise mounted in the same plane with their associated ratchet wheels and are pivotally mounted on studs fixed to the frame members 62 and 63. The actuating pawls 83' and retaining pawls 84' are biased by a spring 86 common to both urging both pawls to rotate oppositely about their respective pivots to hold them into operative cooperation with their associated ratchet wheel 82 unless held out of operative cooperation by the ribbon reversing mechanism in a manner to be explained later. This is also true of the pawls 83 and 84 with respect to the ratchet wheel 81. In the position of the mechanism shown in Fig. 6 the pawls 83' and 84' are coacting with the ratchet 82 it being understood that the pawls 83 and 84 in this instance would be out of cooperation with the ratchet wheel 81.

47 As previously explained, when the handle 5 is lifted to effect printing the lever 56 is caused to rotate clockwise and therefore rotates the shaft 101 likewise. The levers 85 and 85' being fixed to said shafts also rotate clockwise carrying their respective pawls 83 and 83' and as the pawl 83' is the only one in cooperation with its associated ratchet wheel, said ratchet wheel 82 and therefore the ribbon spool 80 is rotated counterclockwise thus winding the ribbon 78 on said spool and unwinding it from the ribbon spool 79.

48 To reverse the feeding of the ribbon there is provided two double cam members 90 and 90' fixed to a shaft 89 journalled in the frame members 62 and 63. Likewise fixed to said shaft is an alining member 95 provided with two alining notches 95'. Cooperating with one of the notches 95' is a roller 96 pivotally mounted on a lever 97 which is in turn pivotally mounted on a stud 97' fixed to the frame member 63. A spring 98 fastened at one end to the frame of the machine and at the other end to the lever 97 holds the roller 96 into cooperation with the alining member 95 thus impositively locking the cam members 90 and 90' into one of the two locking positions made possible by the two alining notches 95'. Fixed to the actuating pawls 83 and 83' are pins 87 and 87' and fixed to the retaining pawls 84 and 84' are pins 88 and 88' respectively. The pins 87 and 88 cooperate with the double cam 90 and the pins 87' and 88' cooperate with the double

cam 90'. As shown in Fig. 6 the pawls 83' and 84' are engaging their associated ratchet wheel 82 whereas the pawls 83 and 84 (not shown in this figure) would be held out of engagement with their associated ratchet wheel by the double cam 90 coacting with the pins 87 and 88. The ribbon as shown in Fig. 6 is being unwound from the spool 81 (not shown) and passes through the bifurcated 10 end of a lever 91, thence between the type wheels and the impression block on the hammer, thence through the bifurcated end of a lever 91' and thence is wound onto the spool 80. The levers 91 and 91' are pivotally 15 mounted on studs 100 and 100' respectively, said studs being mounted in the supporting frames of the machine.

To projections 92 and 92' fixed to one of the furcations of the levers 91 and 91' respectively, are springs 94 and 94'. The opposite end of the spring 94 is fastened to a pin 93 fixed to the upper end of the double cam 90. The opposite end of the spring 94' is fastened to a pin 93' fastened to the lower end of the double cam 90'. These two springs being under no tension resiliently hold the levers 91 and 91' in the position as shown in Fig. 6. Near each end of the ribbon and fixed thereto is an eyelet 99 which projects each side of 25 the ribbon sufficient to prevent its passing through the bifurcations of the levers 91 or 91'.

As previously stated the ribbon 78 is being wound onto the ribbon spool 80 when the ribbon feeding mechanism is in the position as shown in Fig. 6. As the ribbon spool 81 (not shown) becomes almost completely unwound the eyelet 99 coacts with the edges of the bifurcated lever 91 and as the ribbon continues to be fed on to the spool 80 said eyelet causes the lever 91 to turn in a clockwise direction introducing a constantly increasing tension in the spring 94. When the tension of this spring is sufficient to overcome the impositive locking action of the alining member 95 and its coacting spring pressed roller 96, it causes the cam 90 to turn in a clockwise direction to bring the roller 96 into cooperation with the other notch 95' of the alining member 95. The turning of the cam 90 also turns the cam 90' which causes the pawls 83' to be carried out of operating position to a position as shown in Fig. 4 and simultaneously the turning of the cam 90 permits the ratchets 83 and 84 to engage their coacting ratchet wheel 81 as shown in Fig. 3. Thus successive registering operations will now cause the ribbon to be fed in the opposite direction being unwound from ribbon spool 80 onto ribbon spool 79. When the ribbon spool 80 is nearly exhausted an eyelet similar to the eyelet 99 located in the opposite end of the ribbon coacts with the bifurcated arm 91' moving it clockwise about its pivot 100' (Fig. 6) thus introducing tension into the

spring 94' until said spring causes the cam 90' and therefore the cam 90 to turn in a counterclockwise direction thus restoring the pawls 83' and 84' into cooperation with their coacting ratchet wheel 82 and disengaging 70 the pawls 83 and 84 from their coacting ratchet wheel 81.

The time sheet (Fig. 8) is ruled off into a plurality of columns to correspond to the number of printing positions permitted on 75 the time recorder for which said sheet is adapted. All registrations in any one column are thus made by the employee which that column represents.

When a recording mechanism of the character described is used in a business organization the employees who are to register on the clock are given different designating numbers. When an employee arrives at work in the morning he notes that the pointer 32 on the knob 7 is pointed at one of the "In" indexes. If it is not, he turns it to the next adjacent "In" indication. This feeds the paper strip one line and assures him of a clear place in which to register. He then 80 slides the handle 5 transversely until it is under the notch 61 which bears the number by which he is designated and he then lifts the handle into said notch. This causes the time indicated by the clock hands to be printed on the record receiving strip, within the 85 clock, in the column corresponding to that employee's number. The first man that goes out shifts the knob pointer 32 from the "In" 90 indications to the next adjacent "Out" registration so as not to obliterate his previous "In" registration by double printing. The employee following out will find the pointer 95 at the "Out" position and so will not be required to change it.

After a lapse of time corresponding to the payroll period of the business organization has elapsed the time keeper removes the time sheet by moving the finger piece 30 in a manner to cam the pawls operating the receiving roll 13 out of engagement thereby leaving said roll free to be turned in a reverse direction thus permitting the removal of the record sheet. That part of the sheet carrying the printed record is then torn off of the continuous strip and removed and the end of the strip is again clamped on to the receiving roll and the receiving roll operating pawls are restored to their operative position.

The record sheet removed with the printed record thereon such as shown in Fig. 8 therefore forms a complete payroll time sheet.

While the fundamental novel features of the invention as applied to a single modification have been shown and described and pointed out, it will be understood that various omissions and substitutions and changes in the form and details of the device illustrated and in its operation may be made by those skilled in the art without departing from the 125 130

spirit of the invention, I intend to be limited therefore only as indicated by the scope of the following claims.

1. In a time recording apparatus, a time controlled printing device, a carrier for a continuous time sheet and shifting means operable only in one direction to shift said time sheet to subsequent printing positions in linear direction, said shifting means comprising a handle actuating a star wheel which cooperates with a pivoted linkage to oscillate the same for shifting the time sheet, and which linkage in turn cooperates with the star wheel to prevent retrograde movement of said wheel, and means for separately adjusting said time sheet carrier in transverse direction into different printing positions relatively to said printing device.
2. In a time recording apparatus, a time controlled printing device, a carrier for a continuous time sheet, devices mounted upon said carrier and adapted to feed said sheet, a ball for operating said devices in all positions of said carrier, a hand operated means operable only in one direction to actuate said ball to shift said time sheet to subsequent printing positions in linear direction, additional means for adjusting said time sheet carrier in transverse direction into different printing positions relatively to said printing device, and means for effecting a printing impression from said printing device on said time sheet.

In testimony whereof I hereto affix my signature.

FREDERICK L. FULLER.
